HYDRAULIC DRIVES FOR RECTILINEAR ALTERNATING MOTIONS FOR RECIPROCATING MACHINES

Friedrich Klopp, Friedrich Klopp, Jr., and Friedhelm Lessenich, Solingen-Wald, Germany, assignors to Klopp-Werke G.m.b.H., Solingen-Wald, Germany, a corporation

Filed Dec. 31, 1959, Ser. No. 863,208

Claims priority, application Germany Jan. 5, 1959

5 Claims. (Cl. 60—52)

The invention relates to hydraulic drives for rectilinear alternating motions for reciprocating machines, particularly machine tools with a pump connected with the cylinder chambers of the operating cylinder, the discharge quantity of which may be infinitely adjusted by means of a control element through a neutral position to a reverse direction of flow, and provides further improvements of the drive according to the pending patent application Ser. No. 730,567, now Patent No. 2,928,244, dated March 15, 1960. The older patent application relates to a drive of this type in which the control element of the infinitely adjustable pump (generator) may be reciprocated between two extreme positions defined by stop means by a reversing control valve of the piston slide type which is actuated by a control pump. In this arrangement the reversing control valve which is making equal strokes towards both sides of a neutral position corresponding to a discharge volume of zero and the control element of the pump are guided with guide pins in a guide way of a common crank the pivoting point of which is adjustable by a spindle for varying the movements which are of equal magnitude towards both sides of the neutral position. Furthermore, according to the above mentioned older patent application the adjustment of the control pump is coupled with the pivoting point of the crank, so that a certain movement of the pump control valve always corresponds to a proportional adjustment of the control pump. According to another feature of the above mentioned older patent application the control pump is connected in such a way that, besides actuating the reversing control valve and flushing the circulating system, it may also serve as drive of an advance motor the return of which is connected with a proportioning valve the adjustable piston stroke of which defines the magnitude of the feed.

One object of the invention is to provide a further improvement of the advance control in that the actuation of the feed switching device simultaneously takes place with the switching of the reversing control valve by either a direct mechanical connection between the reversing control valve and a ratchet means, or by actuating an advance motor with the oil discharged from the reversing valve upon reverse switching.

Due to this construction the actuation of the feed takes place simultaneously with the reverse switching which constitutes a substantial improvement relative to the operating time as compared with the construction according to the above mentioned patent application, as according to this the advance may not be actuated before the reverse switching is completed.

Another object of the invention is to provide a mechanically operated advance motor for small machines the reversing valve of which being provided on both sides with piston rods extending out of the cylinder, one of which being provided with a rack, or the like, at its end and extending out of the cylinder beyond the piston

2

stroke, said rack cooperating via a pinion with the ratchet wheel of the feed. As the feed only takes place during one stroke, only one of the piston rods needs to cooperate with the ratchet wheel.

Still another object of the invention is to provide for larger machines a hydraulically operated advance motor in which the discharge ducts for the oil expelled from the reversing valve are connected with the cylinder of the control valve for the reciprocating movement of the machine which is actuated by stop pistons, one of the discharge ducts being connected with the feed motor via the cylinder of the control valve and the cylinders of the feed direction pistons, while the other pressure duct communicates with throttle means.

15 15 Two embodiments of the invention are shown schematically by way of examples. In the drawings:

Fig. 1 shows a switching diagram with an actuation of the feed by mechanically connecting the reversing control valve with the ratchet means,

20 20 Figure 1A is a view of the generators and their associated components, and

Fig. 2 shows a diagram for a hydraulic connection of the reversing control valve with the feed motor.

The diagram shown in Fig. 1 corresponds to the 25 illustrated arrangement of the above mentioned older patent application according to Fig. 1, the drive functioning as follows:

The generator G2 is sucking oil out of the container 30 30 through the duct 21 and feeds the pressure oil through the ducts 23, 24, to a precontrol valve K3 and through a duct 25 to the reversing valve K4, thereby moving the reversing valve K4 into its left hand position. In this end position the pressure oil from the generator G2 may flow via a correspondingly switched path to the duct 26.

35 35 In this end position of the reversing valve K4 the pressure oil from generator G1 flows through the ducts 27, 28, 29, the switch valve K2, and duct 30 into the operating cylinder 1 and moves the operating piston K1 downwardly. The oil discharged by the piston K1 returns through the duct 31, the switch valve K2, the ducts 32, 33 and 34 to the generator G1. Flush oil enters the working circuit through the duct 26. Prior to this the surplus oil is leaving the circuit through the duct 35

40 40 (this is achieved by the impossibility of the flush oil to flow against the stream) and flows via the reversing valve K4, the ducts 36, 37, a counter pressure valve V2 and duct 38 into the supply container 22. The valve V2 sets up a small backpressure. The operating piston K1 now moves downwardly working in a closed circuit of the generator G1. The rigidity of the drive and the transmission of heat out of the circuit is secured by the pressure flushing of the output of generator G2.

The switching of the operating piston K1 is in this 45 45 case achieved by electrical means. The limit stop A1, being either connected with the piston rod 2 of the working piston K1 or the machine element to be driven, operates the switch T1 whereby the magnet M4 is energized, thereby moving the piston of the precontrol valve K3

50 50 into the right hand position. When the operating piston K1 moves in an opposite direction the limit stop A2 actuates the switch T2 by which the associated magnet M3 is energized. The reversing movement of the piston of the precontrol valve K3 may be achieved in any other way as well.

55 55 The oil discharged by the generator G2 now flows from the duct 24 via the precontrol valve K3 and duct 39 to the reversing valve K4 which will move towards the right, as the oil is discharged from the duct 25 and flows via the precontrol valve K3 and ducts 40, 41 and 42 to the container 22. In the opposite position of the precontrol valve K3 the oil returns to the container via

the duct 39 via the duct 53 which is connected with the duct 41. A slightly preloaded backpressure valve V3 ensures that the control ducts are filled with oil. Simultaneously with the switching of the reversing valve K4 the generator G1 is moved by the crank 9 into the opposite position of eccentricity. The pressure oil which previously had been flowing to the duct 27 and returned via the duct 34 continuously decreases during this operation. In the neutral position the stream of pressure oil momentarily ceases to flow entirely, and upon exceeding the neutral position towards the opposite position of eccentricity the pressure oil flows to the duct 34 and returns via the duct 27. The direction of movement of the operating piston K1 is thereby reversed and now directed upwardly.

Contrary to the above mentioned older patent application the piston of the reversing valve K4 is provided with piston rods 200 and 201 on both ends, the length of which are so that they extend out of the cylinder 7 when the piston of the reversing valve 4 is in its dead end positions. In addition to this the piston rod 201 is extended still further beyond this. This extension forms a rack 202 which engages a pinion 203 of the ratchet wheel 204.

When the piston of the reversing valve K4 is switched from the left hand position, as shown in the drawing, to the right hand position, the pinion 203 is rotated by the rack 202, and thereby the feed (shown partially at 204a) of the slide, ram or the like of the machine tool is actuated during the return stroke of K1, while during the movement of K4 from right to left the dog of the ratchet wheel operates in the known manner.

The switching diagram shown in Fig. 2 corresponds to the diagram of Fig. 3 of the above mentioned older patent application with the only difference that, according to this invention the feed valve may be abolished. According to the invention the return duct 104 of the reversing valve K4 is connected to the cylinder 206 of the precontrol valve K3. The oil discharged from the reversing valve K4 when moved from right to left leaves the cylinder 206 at 207 and flows into the duct 127. The duct 127 is connected with the feed motor VM via the cylinders of the feed direction pistons K9 and K7.

The other discharge duct 93 of the reversing valve K4 is connected at 208 with the cylinder 206 of the precontrol valve K3. During the movement of the reversing valve K4 from right to left, as illustrated in the drawing, the gear pump ZP feeds oil through the duct 91 to the cylinder of the switch valve K2' and thence via the duct 105 to the cylinder 206 and via the duct 93 to the right side of the reversing valve K4. When switching the reversing valve K4 to move from left to right the oil discharged into the duct 93 flows via this duct 93 through port 208 into the cylinder 206, and thence flows through the duct 106 directly to the throttle DR, and from there via the duct 107 into the container 22. The oil discharged by the gear pump ZP is fed through the cylinder of the switch valve K2' into the duct 105, and thence flows via the cylinder 206 into the duct 104 thus effecting the switching of the reversing valve K4.

The following is a list of components in the embodiment of Figure 2, followed by a description of its operation:

K1—Piston, the piston rod extending to one side and actuating a table, slide or the like.

F1—The greater piston surface of K1.

F2—The annular piston surface formed by piston K1 and its piston rod.

G1 and G2—Double acting, infinitely adjustable pumps.

ZP—A control gear pump.

115, 116—Electro motor with clutch driving ZP, G1 and G2.

K4—Control piston valve with constant stroke.

9—Crank pivoted at 8 on K4 moving G1 and G2 through zero output position, the control position of K4 corresponding to the zero output position of G1 and G2. K10—Pivoting point of the crank 9.

5 10, 16, 17—Pin, spindle and nut for adjusting the pivot point of the crank 9 and thus the pivot angle of G1 and G2.

117—Slide by which G1 and G2 are pivoted by pins 120, 121 and guide slots 118, 119.

10 12—Pin pivotally connecting crank 9 with slide 117. K6—Piston valve for automatically adjusting spindle 16 by gearing 54.

DR—Throttle, simultaneously adjusted with spindle 16 by pair of gears 55 thus regulating the output of ZP proportionally to the outputs of G1 and G2.

15 K3—Precontrol piston valve for K4, controlling ZP to deliver via ducts 91 or 105 into ducts 93 or 104.

T1, T2—Hydraulic contacts consisting of small pistons which are moved upon engagement by the limit stops A1 and A2 thus causing a displacement of an oil column by which K3 is shifted.

K2—Stop valve connecting or interrupting main ducts 85 and 86, thus controlling "stop" or "operation."

VM—Feed motor operating a spindle.

25 K9—Piston valve for feed "on" or "off" by connecting or interrupting the ducts 127, 128.

K7—Piston valve for changing the direction of feed by connecting duct 129 either to duct 130 or duct 131.

K8—Piston valve for changing the direction of feed by adjusting the volume of oil delivered by VM. The adjustment of the oil volume is achieved by the spindle 134.

K10—Piston valve for rapid advance. Held in its position by a spring 142, it interrupts the delivery from ZP via duct 141 as well as the outlet from VM via duct 144. As long as K10 is pushed in VM is running.

K2'—Piston valve for preselecting the rapid advance. In a pulled-out position it connects duct 91 from ZP with duct 141 to K10. In a pushed-in position as illustrated in the drawing K10 is not affected.

In the positions of parts illustrated in Figure 2 G1 and G2 are delivering oil through the ducts 83, 84, 85 to F1 of K1 while latter moves in the direction indicated by the arrow. The oil displaced by F2 flows via ducts 86, 87, 88 to G1. In the direction opposite to the arrow G1 delivers to F2 of K1. The oil displaced by F1 flows via ducts 85, 84, 83 to G2 and G1.

50 Condition for equal volumes within the system

F1:F2=(G1+G2):G1, example: F1=2/F2=1

$$\frac{2}{1} = \frac{G1+G2}{G1}; 2G1 = G2; G1 = G2$$

55 The left hand position of K4 corresponds to a movement of K1 in the direction indicated by the arrow

Control piston K4 is moved to the illustrated position by feeding control oil from ZP via the ducts 91, K2', 105, K3, 208 and 93 to K4. In the end position

60 of K4 the oil flows via the ducts 94, 96 into the ducts 86-89 which are the main return ducts in this instance, and flushes the system with fresh oil. Operating oil is conducted via duct 97 and K4 and ducts 98, 99, 100 to the supply container.

The right hand position of K4 corresponds to a movement of K1 in the direction opposite that indicated by the arrow.

70 Control piston K4 is moved to the right hand position (opposite to that shown) by switching K3 to its other position by means of limit stop A1 actuating the hydraulic contact T1. Now the control oil flows from ZP via 91, K2', 105, K3, 205, 104 to K4. In the end position of K4 the oil flows via duct 112 into the main

duct 83 which in this instance represents the return duct and which is thereby flushed with fresh oil. Through the ducts 113, 114 operating oil flows via K4 and ducts 114, 98, 99, 100 to the container.

The adjustment of the velocity of K1 for the advance and the return stroke is achieved by K6

In the illustrated position (direction of arrow) control oil is fed from ZP via duct 122 to K6 and moves the latter into engagement with the spindle 18. Hand-wheel 13 serves to adjust the eccentricity of the pumps G1 and G2 for the advance (operating stroke) of K1.

During the return stroke (opposite to the direction of arrow) oil is fed to G2 from where it is delivered via ducts 108, 109 to K6 whereby the latter is pushed into its left hand end position (greatest eccentricity of G1 and G2) and flows through duct 110 to the container.

Feed control

Every time K1 changes from return to advance movement K4 is moved from its right hand to its left hand position by feeding control oil to it from ZP via duct 93. The oil thereby displaced flows via 205, K3, 207, 127, K9, 128, 129, K7, and 130 to the feed motor VM.

The oil discharged by VM flows via 131, K7, 132 and 133 to K8. The adjustment of the oil volume determines the number of revolutions of VM. The surplus oil not required for the movement of VM (the total discharge determines the maximum amount of feed) flows via 127a and valve V3 to the container.

During the return stroke of K1, K3 has been moved to its right hand position by means of limit stop A1 and hydraulic contact T1. In this position of K3 K8 can discharge via the ducts 133, 137, 138, K3, 105 into the container. K8 may reassume its preparatory position by moving it toward the left by means of the flushing pressure V2 via ducts 99, 139.

The mode of functioning of the entire drive corresponds to that described in the above mentioned older patent application.

What I claim is:

1. In a hydraulic drive for effecting alternating rectilinear motion, a cylinder, a piston within said cylinder connected to a driven machine member, an advance motor for said member, first and second chambers of varying volume defined by said piston, means for generating hydraulic pressure including a variable delivery pump, conduit means connecting one side of said generating means with said first chamber and connecting the other side of said generating means with said second chamber, an adjusting member movable from a neutral position in either direction for infinitely varying the output capacity of said generating pump and for reversing the flow direction thereof, a reciprocable reversing valve of the piston slide valve type having a valve cylinder and stroke of predetermined length, a precontrol valve of the piston slide valve type responsive to arrival of said piston at a definite position for causing said reversing valve to

shift through said predetermined stroke, connecting means between said reversing valve and said adjusting member for causing a constant shifting of said adjusting member during the movement of said reversing valve, the position of said adjusting member at any instant being proportional to the position of said reversing valve, said advance motor being drivably connected with and operated simultaneously by the stroke of said reversing valve piston.

5 2. The combination according to claim 1, said piston of said reversing valve being provided with rod extensions extending on both sides out of the valve cylinder, one of said rods being provided with a rack at its end extending out of the cylinder beyond the piston stroke, 10 said rack engaging a pinion cooperating with a ratchet wheel of said advance motor.

15 3. In a hydraulic drive for effecting alternating rectilinear motion, a cylinder, a piston within said cylinder connected to a driven machine member, first and second 20 chambers of varying volume defined by said piston, means for generating hydraulic pressure including at least one variable delivery pump, conduit means connecting one side of said generating means with said first chamber and connecting the other side of said generating means with 25 said second chamber, an adjusting member movable from a neutral position in either direction for infinitely varying the output capacity of said generating pump and for reversing the flow direction thereof, a reciprocating reversing valve of the piston slide valve type having a 30 stroke of predetermined length, a precontrol valve of the piston slide valve type, a variable delivery control pump responsive to the arrival of said precontrol valve piston at a definite position for causing said reversing valve to shift through said predetermined stroke, connecting 35 means between said reversing valve and said adjusting member for securing a constant shifting of said adjusting member from one side of its neutral position to the other during the movement of said reversing valve, the rate of movement of said adjusting member being proportional to the rate of movement of said reversing 40 valve, output selector means for varying the proportion of said adjusting member movement with respect to said reversing valve movement, whereby the maximum output of said generating pump may be selected, and 45 means comprising a hydraulically operated advance motor, connected to said precontrol valve, the discharge conduits of said reversing valve being connected with said precontrol valve.

4. The combination according to claim 3, including 50 advance direction piston slide valves, one of said discharge conduits being connected with said advance motor via said precontrol valve and said advance direction valves.

5. The combination of claim 3 including a throttle means with which the other one of said discharge 55 conduits is connected via said precontrol valve.
